UNITED STATES PATENT OFFICE

HENRY A. STUDWELL, OF STAMFORD, CONNECTICUT

ESCAPE TUBE FOR SUBMARINES

Application filed May 21, 1928. Serial No. 279,287.

This invention relates to an escape device by means of which the crew may escape from a submerged submarine, and has for an object to provide a device of this character of simple construction which will be reliable and effective in operation and may be operated by a single man so that the last man may escape.

It is a further object of the invention to provide a device of this character which is not dependent for its operation upon power or machinery which might be put out of order by an accident to the vessel.

It is a further object of the invention to provide a device in which a buoy may be carried and permitted to escape in case of sinking of the vessel to mark its location, and which may also be used for transmitting messages or food to the occupants of the vessel.

With the foregoing and other objects in view, the invention consists in certain novel features of construction, combinations and arrangements of parts as will be more fully described in connection with the accompanying drawings. In these drawings,

Fig. 1 is a side elevation of the device as applied to a submarine certain parts being broken away to more clearly show the construction.

Fig. 2 is a vertical section through the upper portion of the device, the plane of the section being substantially at right angles to Fig. 1.

Fig. 3 is a detail section of the automatic vent valve.

Fig. 4 is a section through the upper end of the device showing the valve for controlling the equalizing pressures in the open position.

Fig. 5 is a side elevation of the lower part of the device showing the closure for the lower entrance opening to the device in closed position.

Fig. 6 is a transverse section substantially on line 6-6 of Fig. 1 and showing the closure for the opening in the open position.

Fig. 7 is transverse section substantially on line 7-7 of Fig. 5, and

Fig. 8 is a partial section and partial ele-

vation of the lower portion of the device showing how the buoy may be carried.

In the drawing the outer shell or upper deck of a submarine is shown diagrammatically at 10, and my improved escape device 55 is mounted to pass through this deck and is exposed at its upper end outside the vessel for escape of the men. It is provided within the vessel with means for gaining access to the device and closing it off from the interior 60 of the submarine. This escape device comprises a tubular casing 11 of suitable size to hold a man. For example, it may be about twenty-two to twenty-four inches in diameter and somewhat over six feet long.

The open upper end projecting above the deck of the vessel is closed water tight by a hinged closure 12 hinged to the casing at 13 and opens by swinging outwardly, as indicated in dotted lines Fig. 1. This closure 70 has an arm 14 connected by link 15 to an operating rod 16 passing through the deck 10 to the interior of the submarine where it is provided with a handle 17 for operating the closure, and may have an eye or hook 18 for attachment of a weight 19 for automatically opening the closure 12 after pressures within 75 and without the device are equalized as will later be described.

Means is provided in the closure 12 for 80 equalizing pressures within and without the casing 11 so that the closure 12 may be opened. Mounted within the closure is a casing 20 carrying a ball valve 21 controlling openings 22 leading to the interior of the 85 casing, and a downwardly inclined tube or opening 23 communicates with the outside of the closure. A spring 24 tends to close the ball valve 21 and hold it against its seat to close the openings 22. The valve may be 90 opened by means of a lever 25 pivoted to the closure at 26 and engaging a rod or pin 27 extending to the ball valve. The lever is normally raised by a spring 28 permitting the valve 21 to close and a suitable cable or 95 other means 29 may be provided for operating the lever 25. It will be apparent that by pulling downwardly on the lever 25 the pin 27 will be forced against the valve 21 lifting this valve from its seat and opening com- 100

munication from the interior of the casing 11 to the water outside the closure. Water will, therefore, flow into the casing 11 through the openings 22 and 23 until the 5 pressure within the casing 11 is the same as that outside the closure.

Means is provided for venting the air in the casing 11 while this water is flowing into it. For this purpose a pair of vent pipes 30 10 lead from the upper portion of the casing and preferably extend down through the deck to the interior of the submarine so that the air is vented back into the interior thereof instead of being lost. These tubes may be 15 closed by hand valves 31 from the interior of the vessel, and they have automatic valves shown more clearly in Fig. 3. The entrance to the tubes is provided with a valve seat 32 and this end of the pipe is enclosed in a casing 33 closed at its lower end by an inclined wall 34. A ball float valve 35 is in this casing and it is normally in the lower part thereof, as shown in Fig. 3. An entrance opening 36 is provided in the side of the casing. 20 As the water rises within the shell or casing 11 air is forced through the opening 36 and vent tube 30 until the water reaches the opening 36 when it will flow into the casing 33 and raise the float valve 35 against the seat 32 and prevent water flowing through the 25 pipe 30.

I have also provided an improved means for permitting access to the interior of the tube 11 from a submarine compartment. For 30 this purpose the side of the casing is provided with an opening 37 of any suitable shape but preferably elongated vertically to facilitate the entrance of a man into the casing. The casing is enclosed by a suitable closure 38 which is mounted to turn about the casing and has an opening 39 of substantially the same size and shape as the opening 37 in the casing. This closure is mounted on suitable bearings on the outer wall of the casing, 35 and to facilitate operation of this closure ball bearings 40 and 41 are preferably used at the opposite ends of the closure. A vertical rod 42 extends between the flanges 43 at the opposite ends of the closure and forms a convenient handle for operating the closure. At 40 one side of the openings 37-39 the casing and closure are provided with aligned recesses 44 and 45 to permit a person within the casing 11 to pass his hand through and grasp the rod 42 to partially close the closure 38. The closure 38 is provided with a recess or 45 opening 46 in the inner wall which opening is closed by a plate 47 and is arranged in alignment with the recess 44 and is so positioned that when the closure is partly closed this recess 46 is accessible through the opening 37 in the casing and the person within the casing may place his hand within this recess 46 and move the closure to the completely closed position of Fig. 7. Thus by

this arrangement the closure may be operated by a person within the casing and the last man may operate the escape device and be saved.

The operation is as follows: With the closure 12 closed the closure 38 may be opened, as shown in Fig. 1, and a man may pass through this opening into the casing 11. The closure 38 may then be closed, as shown in Figs. 5 and 7, either from the outside by a person still in the submarine, or it may be closed by the man himself within the casing. The man may then open the valve 21 by pulling on the lever 25. This permits water to flow into the casing 11 and equalize the pressure therein with that of the water outside the vessel, the air in the casing 11 being vented through the pipes 30. Previous to entering the casing 11 the man may protect himself with a suitable helmet and apparatus for supplying oxygen for sufficient time to keep him alive while he is in the casing 11. He may also put on a protection for the upper portion of his body against the heavy pressure of the water outside the vessel.

After the pressure within the casing 11 is substantially the same as that of the water outside the man in the casing may open the cap 12 by pushing it upwardly and thus escape to the surface, or the cap 12 may be opened by persons within the submarine pulling down on the handle 17, or it may open automatically by the weight 19 as soon as the pressures are equalized.

After the man has escaped the closure 12 may be closed by manipulation of the handle 17, thus sealing the upper end of the casing 11, and then the closure 38 may be opened permitting the water in the casing to run out. As this is a comparatively small amount of water it will not materially cut down the air space within the submarine compartment. Another man may now take his place within the casing 11 and the operation repeated until all the men escape.

The casing 11 may be employed for carrying a signal buoy 48 (Fig. 8) connected by means of a flexible cable 49 to an anchorage (not shown) within the submarine. This buoy may be released prior to the escape of men to signal to people on the surface of the water or to indicate the location of the sunken vessel. For this purpose the operating member 29 for the ball valve 21 in the cap 12 may be extended down through the lower head 50 of the device where it may be operated from the interior of the vessel to permit opening of the closure 12. The buoy 48 may then be allowed to float to the surface, and this buoy may be provided with a chamber closed by a door 51 in which food or messages may be sent to the parties in the vessel. If the device is intended to be used for escape from the submarine the anchoring cable 49 may be released to permit closing of the cap 12.

I have provided a device whereby water may be forced out the upper end of the casing 11 if it is found undesirable to permit this water to flow from the casing into the submarine after a man has passed out through this device. For this purpose a piston 51 fitting the interior of the casing is mounted to reciprocate therein, it being normally in position at the lower end of this casing. The head 50 is carried on a suitable ring 52 which may be supported to turn on the casing 11 by suitable ball bearings 53 so that it is operated with minimum friction, and it has threaded engagement with a stem 54 secured to the piston 51. The head 50 may be rotated by suitable means, such as handles or hand pins 54 and thus reciprocate the piston 51. As the pressure within the casing may be quite large the thread of screw 54 should be of a comparatively small lead or pitch. This may be operated after the man or buoy has been released through the upper end of the casing 11 to force water out of the casing. The closure 12 may then be closed and after the piston has again been withdrawn to its lower position the closure 38 may be opened. It will, of course, be necessary before operating the head 50 to release the cable 49 and detach the operative connection 29. It will also be understood that the piston and the rod 16 as well as the closure 38 is provided with suitable packing to prevent leakage, although this packing is not shown as it may be any of the conventional types. To prevent rotation of the piston 51 in the casing, guides 55 may be provided on the interior of the casing cooperating with suitable notches or recesses in the piston.

In order to protect the projecting portions of the device from injury by a block of ice or other floating objects a guard 56 may be provided on the deck of the vessel in front of the device.

It will be apparent from the foregoing description that the device is very simple in construction and may be easily manipulated by one man so that the last man may escape from the vessel without difficulty.

Having thus set forth the nature of my invention, what I claim is:

1. An escape device for submarines comprising a tubular casing adapted to project through the deck of the submarine, a hinged closure for the upper end of said casing and opening outwardly, said closure being provided with an opening closed by a valve, operating means carried by the closure for manually opening the valve and for automatically reclosing it, said casing being provided with an entrance opening within the submarine, and means for closing said opening operable from within the casing.

2. An escape device for submarine comprising a tubular casing projecting through the deck of the submarine, a hinged closure

for the upper end of said casing opening outwardly, said closure being provided with an opening for equalizing pressure controlled by a valve, means for operating said valve, a connection from said closure to the interior of the submarine, a weight connected to said connection for automatic opening of the closure as soon as the pressures within and without the casing are equalized, said connection having means for manually closing and opening said closure, said casing having an entrance opening within the submarine, and a closure for said opening operable from within the casing.

3. In an escape device for submarines, a tubular casing extending through the deck, a hinged closure for the upper end of the casing opening outwardly, means controlled from within the casing for neutralizing the pressure within and without the casing, said casing being provided with an entrance opening in its side wall, a closure for said opening mounted to turn on the casing, and means for operating the closure from within the casing.

4. In an escape device for submarines, a tubular casing extending through the shell thereof, a closure for the outer end thereof, means for equalizing pressure within the casing with that outside the vessel, said casing being provided with an entrance opening for a man through its side wall, a tubular closure mounted to turn about said casing and provided with a similar opening adapted to be brought into alignment with that in the casing, and means for operating said tubular closure.

5. In an escape device for submarines, a tubular casing extending through the shell thereof, a closure for the outer end thereof, means for equalizing pressure within the casing with that outside the vessel, said casing being provided with an opening in its side wall, a tubular closure for said opening mounted to turn about the casing and having a similar opening adapted to be brought into alignment with that in the casing, means on the outside of the closure for operation thereof to a partially closed position by a person in the casing, and means on the interior of said closure which becomes accessible to the operator by partial closing movement and is adapted to complete the closing of the closure.

6. In an escape device for submarines, a tubular casing extending through the shell thereof, a hinged closure for the outer end thereof opening outwardly, a valve controlled communication between the interior and exterior of said casing to equalize the pressure therein with that of the water outside the vessel, means for operating the closure, means for operating the valve, a piston fitting the interior of the casing, a rotatable

head at the lower end of the casing, a rod
for the piston having threaded connection
with said head, means for rotating the head,
said casing having an entrance opening
therein within the vessel, and a closure for
said opening.

In testimony whereof I affix my signature.
HENRY A. STUDWELL.
